WILLIAM G. SEMPLE, OF CINCINNATI, OHIO.

Letters Patent No. 92,660, dated July 13, 1869.

COOKING-STOVE.

The Schedule referred to in these Letters Patent and making part of the same.

To whom it may concern:

Be it known that I, WILLIAM G. SEMPLE, of Cincinnati, Hamilton county, Ohio, have invented certain new and useful Improvements in Cook-Stoves; and I hereby declare the following to be a full, clear, and exact description thereof, reference being had to the accompanying drawings, making part of this specification.

This is an improvement in the class of stoves which are convertible from a four to a six-hole stove, or the reverse, so as to save the dealer the expense of keeping up a full assortment of both sizes; and

My invention consists in a new and useful arrangement of flues and extension-top, combining the advantages of compactness, and economy of space, material, and heat.

Figure 1 is a perspective view of a four-hole cook-stove, whose top plate is made in the customary pieces A. B.

Figure 2 represents the same stove, after the portion B has been removed, and with the "addition" about to take its place.

Figure 3 is a longitudinal section of the rear part of a stove, with my addition.

Figure 4 is an enlarged view of my damper-handle.

A and B represent a customary divided top for a four-hole cook-stove.

C C' are side plates, and D the rear plate thereof.

E E' are flue-strips, which, in conjunction with the customary side and rear plates C C' and D and the back oven-plate F, form two diving-flues, G G'.

Resting on the top oven-plate H, and inclined rearwardly between the flue-strips E E', is a deflecting flue-plate, I.

The flue-strip E' is perforated, and the flue-strip E and side-plate C are notched, in the manner shown, to receive the shaft J of a damper, K, which, when elevated, as in fig. 3, acts in conjunction with the plate I, to deflect the heat and flame upward to the two supplementary boiler-holes L L' before passing down the diving-flues G G', and which, in the depressed condition represented in fig. 2, permits the smoke to escape directly into the chimney.

My addition consists essentially of two plates, O and P, of which the plate O is in skeleton form, so as to present no obstruction to the communication with the interior, and has orifices, o, to receive customary bolts, by which it is fastened to the body of the stove; and the plate P is boxed upward, as shown, so as to afford a stepped or elevated boiler-top, Q, and has orifices, p, to receive bolts or rivets, by which it is attached to the plate O.

The plate P has shouldered flue-strips, R R', which form an upward continuation to the strips E E', and afford, in conjunction with the elevated top Q, a seat or bearing for the damper K in its closed or upper position.

The plates O and P have a slight rear extension, S, for a customary collar, T, to which the stove-pipe is connected.

The shaft of the damper K has a hinged handle,

U, having a lip, u, adapted to engage in a rack, V, upon the side of the plate P, so as to enable the damper to be set to the closed, or any partially-open position.

The side-plate C may have a similar rack, V', for a similarly-hinged handle of the ordinary damper, where only four holes are used.

The ogee or wave-like surface presented by the plate I and damper K, is very effectual to deflect the heat and flames upward against any vessels placed upon the supplementary holes; and the supplementary flue-space M, being in direct communication with the flues G G' and top flue N, without any intervening plate, and, in fact, constituting a part or continuation of those flues, the heat is believed to be applied more promptly and fully to the vessels than in any other form of extension or additional stove-top.

While describing the preferred form of my invention, to vary the same in non-essentials. For example: A stove having but one or two boiler-holes, may be increased to two or four holes in the above manner.

The advantages claimed for this arrangement, over its nearest analogues, are—

First, great compactness; taking up scarcely any more room from front to rear than a common "four-hole."

Second, economy of heat. The portions M of the flue being merely a direct continuation upward of the ordinary flue, instead of a "chamber," separated by the top plate of the stove-body or the bottom plate of the extension, (as in the Vedder, Thornilly, and others of that class,) the vessels being right over the open flue of the stove proper, and receiving the heat therefrom, deflected upward by the reversely-curved plates I and K; the action of cooking is expedited.

Third, economy of material; avoiding an intervening plate, and any considerable extension rearward.

I claim herein as new, and of my invention—

1. The convertible four and six-hole cook-stove, substantially as set forth.

2. The elevated and open-bottomed addition O P, to replace the rear top plate B of an ordinary four-hole cook-stove, in the manner described.

3. The skeleton plate O, boxed or elevated plate P, flue-strips R R', deflecting-plate I, and damper K, the whole being arranged and operating as set forth.

4. The arrangement of hinged damper-handle U, and rack V, for the objects herein designated.

5. In combination with the strips E E' and R R', or their equivalents, the deflector I and damper K, formed and arranged as and for the purposes set forth.

In testimony of which invention, I hereunto set my hand.

W. G. SEMPLE.
